Primary Examiner — Jennifer Rivard

(74) Attorney, Agent, or Firm — Warner Norcross + Judd LLP

(57) CLAIM

We claim the ornamental design for a makeup palette, as shown and described.

DESCRIPTION

The single FIGURE is a top plan view of a makeup palette. The evenly spaced broken lines illustrate a portion of the makeup palette and form no part of the claimed design. The dash-dot-dash broken lines illustrate the boundaries of the makeup palette and form no part of the claimed design.

1 Claim, 1 Drawing Sheet
